UNITED STATES PATENT OFFICE.

DUGALD C. JACKSON, OF MADISON, WISCONSIN.

MOTOR-STARTING RHEOSTAT.

No. 829,272.

Specification of Letters Patent.

Patented Aug. 21, 1906.

Application filed May 21, 1906. Serial No. 318,017.

To all whom it may concern:

Be it known that I, DUGALD C. JACKSON, a citizen of the United States, residing at Madison, in the county of Dane and State of Wisconsin, have invented new and useful Improvements in Motor-Starting Rheostats, of which the following is a full, clear, concise, and exact description, reference being had to the accompanying drawings, forming a part of this specification.

My invention relates to improvements in motor-starting rheostats, particularly that class of rheostats provided with switch-levers adapted to close separately and independently, one of which forms the starting-lever and is retained in the on or running position by an electromagnet responding to "no voltage" or the failure or abnormal decrease of current to release said lever and the other of which levers is associated with an electro-responsive device adapted to release the same to affect the circuit upon the occurrence of an overload or abnormal increase of current.

The main object of my invention is to provide, in connection with these two levers, a lock to prevent the starting-lever from being closed until the overload-lever is closed.

Figure 1 is a face view of a starting-rheostat embodying my invention and in which the two levers are shown in their closed positions, the electrical connections of the various elements of the rheostat and the rheostat itself, with a shunt-motor, being also diagrammatically shown in this figure. Fig. 2 is a face view in which the two levers are shown in open position. Fig. 3 is a detail sectional view taken on the dotted line 3-3 of Fig. 2, but showing the lower part of the pivot-post in elevation. Fig. 4 is a detail view of the lever pivotal mounting. Fig. 5 is a sectional view taken on the dotted lines 5-5 of Fig. 2. Fig. 6 is a similar view, but showing the overload-lever in the closed position; and Fig. 7 is a detail view of the stop-lever.

Referring to the drawings, the reference-numeral 6 designates resistance-coils or the like connected in the usual manner to the contact-buttons 7 on the insulating top or face plate 1 of the starting-rheostat. Switch-levers 10 and 11, having operating knobs or handles 12 and 13, are mounted on a pivot-post 14, which is secured to the plate 1 of the rheostat. These levers are held normally in the open position by the springs 15 and 16,

the spring 16 being secured to the pivot-post 14 and pressing against a pin 17 on the lever 11, while the spring 15 is secured to a boss on the lever 11 and presses against a pin 18 on the lever 10. The pin 18 carries a resilient buffer 19, which strikes against the lever 10 when both levers are thrown to the open position.

The arrangement of the circuits (shown diagrammatically in Fig. 1) and the connections thereto are as follows: The opposite sides of the circuit to the motor are carried from the supply-mains through a double-pole hand-switch 2, one side branching and leading to the field-winding 3 of the motor, while the other branch 20 leads to the armature 4. The other side 21 passes to the terminal post 5 of the starting-box, thence through the overload release-magnet 22 to the contact-button 23, and when the lever 10 is over contact-button 23 and the lever 11 is over one of the live contact-buttons 7 the circuit is completed through the levers 10 and 11 and current may pass from the side 21 through the armature 4 of the motor, since the last contact-button on the top of the rheostat is electrically connected to the terminal post 9 of the rheostat and in turn is connected by the conductor 28 with the armature 4 of the motor. The field-circuit may be traced from any one of the contact-buttons 7 upon which lever 11 may be resting through the no-voltage release-magnet 24 to the terminal post 8 and thence through the motor field-winding 3 to the junction with the armature branch 20.

The switch-lever 10 is provided with a pin 26, which when the lever is moved into contact with the contact-button 23 is engaged by the hook on one of the arms of the dog 25, pivotally mounted at 28 on the top of the rheostat and preferably provided with a coil-spring about its pivot to tend to hold the dog in the position shown in Fig. 1. The other arm of the dog rests normally against the head 27 of the plunger 28, which works through a sleeve 29, positioned to extend within the solenoid 39 of the overload-release-magnet 22. The core 30 of the overload-magnet rests normally upon the upper end of the screw 31, which works through the bottom of the bracket-frame 32, which is secured to the overload-magnet shell. The head on the core 30 may be utilized as a pointer or index, and the frame 32 is provided with graduations, as shown, to indicate

the strength of current which is to actuate the magnet. When the core 30 is adjusted by the screw 31, the latter may be locked in position by the lock-nut 33. The lever 11 when in the open position has the lower portion of the pin 17 abutting against the stop 35 on the stop lever or catch 34, which lever or catch is pivotally mounted at 40 to move vertically in a recessed portion 41 in the top plate of the rheostat 1. The lever is supported near its outer end by the spring 36, which is secured by a screw 37. The stop 35 prevents the closing movement of the lever 11 toward the right until the lever 10 is closed—that is, moved into contact with button 23—thereby rubbing over the upwardly-canted end of the lever 34 to depress said stop 35. As before-mentioned, when the overload switch-lever 10 is moved over the contact-button 23—that is, is closed—it is caught in position by the hook 25. The underload switch-lever 11 can then be moved to the right or closed to gradually cut out resistance in the motor-circuit. When the lever 11 has been moved to the right to a position over the last contact-button 7, should the voltage not be below a predetermined limit the armature 42, carried by the lever 11, will be attracted by the no-voltage magnet 24 and said lever be thereby held in that position.

It will be understood that in the above arrangement of the devices and circuits connected thereto should the lever 10 be released by the overload-magnet 22 acting on the hook-lever 25 the spring 15 will throw it into the open position, thereby breaking the circuit, and that in case of failure of current upon the line from any cause or an abnormal decrease of current in or the opening of the field-circuit the no-voltage magnet 24 is caused to release the lever 11, which is returned by its spring to the initial position. It will also be understood that should an overload occur while moving the starting-lever 11 to the right the lever 10 will be thrown to the open position and the no-voltage magnet 24 will be deenergized and will not hold the lever 11 in the on position. When the starting-lever 11 is released by the no-voltage magnet and is thrown to the open position by the spring 16, the lower end of the pin 17 travels over the inclined stop 35, which readily depresses and again resumes the normal position when the pin 17 has passed completely over it. This interposes said stop in the path to the right of said pin, whereby the lever 11 is locked in open position until the lever 10 is moved into position over the contact-button 23, as hereinbefore mentioned.

Having thus described my invention, what I claim as new, and desire to secure by Letters Patent, is—

1. In a motor-starting rheostat, the com-

bination with a starting-lever and an overload-lever, an electromagnet to retain the starting-lever in the final or "on" position, said magnet being responsive to the failure or abnormal decrease of current in the circuit to release said lever, an electromagnetic device responsive to an overload or abnormal increase of current to release said overload-lever, and a locking device to prevent closing the starting-lever until the overload-lever is closed.

2. In a motor-starting rheostat, the combination with a starting-lever and an overload-lever mounted upon the same pivot, a magnet to restrain the starting-lever in the final or "on" position and responding to failure or abnormal decrease of current to release said lever, an electromagnetic device associated with the overload-lever responsive to overload or abnormal increase of current to release said overload-lever, and a lock to prevent closing the said starting-lever until the said overload-lever is closed, substantially as described.

3. In a motor-starting rheostat, the combination with two spring-actuated levers mounted upon the same pivot, one of said levers being the starting-lever of the rheostat and the other the overload-lever, an electromagnet associated with said starting-lever to retain the same in the final or "on" position to the lever and responsive to the failure or abnormal decrease of current in the circuit to release said starting-lever, means to restrain said overload-lever in its closed position, an electroresponsive device in the circuit to release said means upon the occurrence of an overload or abnormal increase of current in the circuit, and a lock between said levers to prevent the closing of the starting-lever when the overload-lever is open, said lock being prevented from acting when the overload-lever is in its closed position, substantially as described.

4. In a switching device, the combination of two switch-levers mounted on the same pivot, two electromagnets respectively adapted to act each upon one lever, one electromagnet being associated with its lever to release it upon the failure of current or abnormal decrease of voltage and the other electromagnet associated with its lever to release it upon an excessive flow of current, means for opening each switch upon releasing its lever, a handle on each lever affording opportunity for the individual movement thereof, and means to prevent closing the underload-lever unless the overload-lever is closed.

In witness whereof I have hereunto subscribed my name in the presence of two witnesses.

DUGALD C. JACKSON.
